(57) **CLAIM**

The ornamental design for a mandoline slicer, as shown, and described.

DESCRIPTION

FIG. 1 is a perspective view of a mandoline slicer;
FIG. 2 is a top view thereof;
FIG. 3 is a right side elevation view thereof (with the left a mirror image thereof);

FIG. 4 is a rear elevation view thereof; and,
FIG. 5 is a front elevation view thereof.

The dashed lines depict portions of the mandoline slicer that form no part of the claimed design.
